SUPERCHARGED COMPRESSION-IGNITION
INTERNAL-COMBUSTION POWER UNIT

Francis Marburg, St. Petersburg, Fla.

Application December 31, 1943, Serial No. 516,555

16 Claims. (Cl. 123—176)

My invention broadly refers to improvements in supercharged, compression-ignition, internal combustion power units. The present application is a continuation, in part, of my co-pending U. S. patent application Ser. No. 501,436, of September 6, 1943, for improvements in supercharged, compound, Diesel engines. More specifically it refers to improvements in internal cylinder and piston cooling, similar to that shown and explained in my U. S. Patent No. 2,310,643 of February 9, 1943. The main object of the present invention, is, to create a perfectly reliable, highly supercharged power unit, of plain construction, forming a requisite basis for a compound Diesel engine, preferably of similar type as shown and explained in my U. S. Patent No. 2,309,968 of February 2, 1943, and in my above said co-pending U. S. patent application.

In order to clearly understand the purpose of the invention, one must realize, that a highly supercharged power unit of a given cubic piston displacement, at normal engine torque, may be charged with several times the weight of highly compressed air and of fuel, as a non-supercharged power unit of same cubic piston displacement, resulting in several times as high M. I. P., and in much higher mean temperatures than normally obtained in non-supercharged power units. For these reasons, it is advisable, or necessary, to maintain the maximum gas-pressure per sq. i. and the maximum gas-temperatures, within safe limits. In applicant's power unit, maximum gas-pressure and maximum gas-temperatures are maintained lower than in some of the present non-supercharged, high speed power units, whereas the gas-pressure and gas-temperatures, during axially middle and axially inner piston positions, are very much higher than in non-supercharged power units, requiring novel, practically instantaneous, powerful internal cylinder and piston cooling, in order to prevent burning of axially outermost cylinder wall portions, exposed to intense heat during relatively large angular crank movements, and in order to facilitate lubrication of axially middle and axially inner power cylinder wall portions.

Heretofore, the writer provided intermittent, powerful internal cooling of axially outer and axially middle cylinder wall portions, by employing an extremely large amount of powerfully twirling cool scavenging air, and by simultaneously and successively providing additional, separate, intermittent, strong internal fluid-cooling of axially middle and axially inner power cylinder wall portions. This separate internal

fluid-cooling was accomplished by applicant heretofore, by producing strong cooling-air suction within a cooling-fluid passage formed between axially middle piston portions and the cylinder 5 and the cylindrical crosshead guide during the inward piston stroke, whereupon compression of the sucked-in air and cooling-air movement were produced by the reciprocating cylindrical crosshead of larger diameter than the power piston 10 diameter during the outward piston stroke, the crosshead and crosshead guide, together with the valves, acting as a reciprocating cooling-air pump. The writer heretofore suggested that an additional, separate cooling-air pump be employed, besides the pumping action produced by the reciprocating cylindrical crosshead and the crosshead guide. In other words, in his above 15 mentioned previous constructions, applicant produced strong cooling-air movement through a cooling-fluid passage formed between the piston and the cylinder, the cooling-fluid successively flowing also through his hollow power piston, strongly internally cooling the power cylinder and power piston. Applicant nevertheless realizes, that reciprocating pumping action, such as 20 shown and explained by him heretofore, at best, can only produce intermittent or variable cooling-fluid movement through a cooling-fluid passage or passages. Internal cooling of the axially middle and axially inner power cylinder portions and 25 of the power piston, by means of cooling fluid, as stated, mainly depends on heat-convection, which is directly proportional to the weight and velocity of the cooling-fluid contacting the internal power cylinder and the internal power piston-wall surface. In order to produce most 30 efficient internal fluid-cooling, with least loss of energy, cooling-fluid movement should be as steady and as rapid as possible, at uniform, moderate cooling-fluid pressure throughout the 35 pipes and ports and cooling-fluid passage or passages, causing the greatest possible weight of cooling-fluid, to move at highest velocity, through the cooling-fluid passage or passages. It is impossible, to produce steady flow of cooling-fluid, 40 in one direction, if the crosshead, as in applicant's previous constructions, is of larger diameter than the power piston, causing irregular pumping action, even if separate additional means are provided, for producing cooling-fluid-movement 45 through the passage or passages. On the contrary, it is important, that the power piston and power cylinder and the crosshead and crosshead 50 guide, should be of the same diameter and bore,

respectively, producing a cooling-fluid passage of constant cubic content during the reciprocating piston motion, non-disturbing steady cooling-fluid movement through the passage or passages. Steady cooling-fluid movement through the passage or passages, preferably is produced solely by a centrifugal-or turbine-blower or-pump, or the like, or if cooling-lubricant is employed instead of cooling-air, steady cooling-lubricant movement may also be produced by gravity or other known, convenient means. Only in applicant's construction does it become possible, to produce steady, undisturbed rapid cooling-fluid movement through the cooling-fluid passage or passages, at moderate, steady cooling-fluid pressure, which is especially of great importance, if cooling-lubricant is used for internal cooling, particularly at high piston velocity and revolutions, such as employed in high speed Diesel power units. Experience has shown, that reciprocating pumps, moving non-compressible liquids, such as cooling lubricant, at high piston-and reciprocating speed, are causing hammering and breakage or serious wear and tear of valves, as well as loss of much energy. It is evident, that reciprocating pumping action, such as set forth and explained by applicant heretofore, under otherwise similar conditions, produces far less average cooling-fluid velocity solely in one direction, as centrifugal or turbine pumps, a reciprocating pump therefor producing far less internal power cylinder-and power piston-cooling. The above mentioned disadvantages, resulting from applicant's previous constructions are entirely avoided in applicant's present, novel, more plain construction, set forth and explained herein-after, wherein the cylinder is of uniform bore and wherein the power piston and the crosshead are of one and the same diameter.

Another important novel feature, wherein applicant's present construction differs essentially from some of his previous constructions, is, that in the latter, a portion of the cooling-fluid or cooling-air, was forced to flow from the cooling-fluid passage, into and through the combustion products outlet port. This is not the object of the present construction. On the contrary, the combustion products outlet port and the power piston, are now arranged and constructed in such manner, that leakage of cooling-fluid from the cooling-fluid passage into and through the combustion products outlet port is prevented. This is essential, in case cooling-lubricant is moved through the passage or passages, which is preferable in connection with applicant's present novel construction. The writer provided special, novel means, preventing cooling-lubricant leakage, as set forth and explained hereinafter.

Other novel features of construction will be set forth and explained.

Before entering into the description of the attached drawings, applicant desires to explain the meaning of expressions frequently occurring in the specification and claims.

"Axially" means in the direction of the cylinder axis. "Axially outer cylinder and piston portions," refers to portions further removed from the engine crankshaft or powershaft, while "axially inner cylinder-and piston-ports," refers to portions nearer to the crankshaft or powershaft. "Outer" and "inner" and "outwardly" and "inwardly," are understood in similar manner, unless differently specified.

Referring now to the attached drawings, wherein the same numbers refer to same parts

and to same ports and passages, etc., Fig. 1 illustrates a cross-section through the engine in a vertical plane through the crankshaft axis. Fig. 2 represents a horizontal cross-section through the engine on line 2-2 of Fig. 1. Fig. 3 shows the novel piston in erection and a vertical cross-section through the cylinder on line 3-3 of Fig. 1. Fig. 4 is a horizontal cross-section of the piston and cylinder on line 4-4 of Fig. 3. Fig. 5 represents a vertical cross-section through another novel piston and cylinder. Fig. 6 is a horizontal cross-section on line 6-6 of Fig. 5. Fig. 7 illustrates a horizontal cross-section on line 7-7 of Fig. 5. Fig. 8 represents a horizontal cross-section on line 8-8 of Fig. 1. Fig. 9 is a horizontal cross-section on line 9-9 of Fig. 1.

Referring now specifically to Figs. 1, 2, 3 and 4, the engine casing 11 is secured to the crank-case 12, in similar known manner, as shown and explained in applicant's above said U. S. patents. The engine cylinder 13'-13", as shown, is continuous and of uniform bore throughout and is screwed into the engine casing. The axially outer cylinder portions 13', are serving as power cylinder. The piston consists of axially outer piston portions 14', serving as power piston, having piston rings 15 and sliding snugly within the power cylinder, and of axially middle piston portions 14 and of axially inner piston portions 14". The axially inner piston portions are of the same diameter as the power piston and are serving as cylindrical crosshead, sliding snugly within the axially inner cylinder portions 13" serving as cylindrical crosshead guide. The crosshead and crosshead guide are taking up all sidethrust produced by the connecting rod 17, while driving the crankshaft 17'. The axially middle piston portions 14 contain a cavity, serving as a reciprocating cooling-fluid passage 18, of constant cubic contents, formed between the axially middle piston portions and the cylinder. A cooling-fluid inlet port 19 is provided for the cooling-fluid passage 18.

As illustrated, the hollow power piston 14' has a hollow axially inward extension, screwed onto a hollow axially outward extension of the crosshead 14", the two extensions, together, forming the axially middle piston portions 14. A hollow tubular conduit 16 is screwed into the axially inward extension of the hollow power piston and, as shown, is reaching outwardly, partly through the hollow power piston, to adjacent to the power piston top, the conduit 16 subdividing the space within the power piston into a radially outer, annular shaped, second reciprocating cooling-fluid passage 16' and into an interior space 16", the latter space communicating with the passage 16' adjacent to the piston top. Perforations are provided within the axially middle piston portions adjacent to the power piston, the perforations serving as second cooling-fluid ports 20, permitting communication between the axially outer end of the reciprocating cooling-fluid passage 18 and the second reciprocating cooling-fluid passage 16'. The radially interior space 16" is communicating at its axially inner end with the hollow 17" within the inner end portion of the axially middle piston portions. The power unit has a third cooling-fluid port 21, passing through the wall of the inner end portion of the axially middle piston portions, adjacent to the crosshead, permitting the hollow within the axially middle piston portions to communicate with a second cavity 18', provided between the axially middle piston

portions, the second cavity serving as a third reciprocating cooling-fluid passage of constant cubic contents, the latter cooling-fluid passage being separated from the cooling-fluid passage 18 by longitudinally arranged webbs 25', (see Fig. 3), arranged on the axially middle piston portions and the cylinder, a fourth cooling-fluid port 19' being provided, communicating with the third cooling-fluid passage 18'. All of the aforesaid cooling-fluid ports and cooling-fluid passages, together, are forming a group and are arranged in series and in permanently open communication with each other. In addition to the above mentioned cooling-fluid ports and passages, a fifth cooling-fluid port 20' is provided, passing through the wall of the axially outer end of the hollow middle piston portions, adjacent to the power piston, as shown, permitting a portion of the total amount of cooling-fluid to flow from the second cooling-fluid passage 16', directly into the third cooling-fluid passage 18'. The cooling-fluid port 20' is of importance for reasons explained hereinafter. A cooling-fluid pump or blower 22, preferably of centrifugal-or turbine-type, forces cooling-fluid to move steadily, rapidly, solely in one direction, throughout all of the ports and passages, which together are forming a group of constant volume or cubic content, at moderate, constant cooling-fluid pressure, producing almost instantaneous internal fluid-cooling of large portions of the cylinder surface, which are intermittently, successively, exposed to the hot piston and piston rings and to cooling-fluid during the reciprocating piston motion. As illustrated, the power piston, as well as the cylinder, are strongly internally fluid-cooled. As furthermore shown, the cylinder is simultaneously externally liquid-cooled throughout its length, by permitting cooling-water to enter into the main power unit casting through the pipe 23 and to overflow through the pipe 24. The cylinder and power piston and the cylinder head 25, preferably are, manufactured of high percentage chromium steel, or the like. The manner in which the cylinder head is forced gas-tight onto the cylinder, by pressure exerted on the spray valve casing 26, by the top plate 27, has been fully set forth and claimed by the writer in his previous U. S. patents and therefore requires only few explanations. It is sufficient, to state, that the guide 28 for the spray valve casing 26, as shown, is screwed into an outward extension 29 of the engine casing and is perfectly aligned with the engine cylinder and with the axially outer conical bore 30 within the cylinder head. The cylinder head has a port 31, serving as fuel-inlet port, terminating into the compression chamber 32, formed between the cylinder head and the piston top while the piston is in axially outer dead center position indicated by the dotted line 33. The fuel is injected very gradually during beginning of the power stroke, thus avoiding excessive maximum gas-pressures and gas-temperatures. The novel manner of producing perfect, almost instantaneous combustion, with late fuel injection, has been fully set forth and explained by applicant in his above said U. S. patents, but should be explained herein again.

Fuel is injected into the compression chambers of Diesel engines at initial velocities of fuel drops of between 500 ft. and 1000 ft. per second, at fuel pressure varying in different types of engines between 3000 lbs. and 15,000 lbs. per sq. in. At these initial velocities, fuel drops instantly flatten and break up into minute drops, together offer-

ing a relatively very large total heat-exposed surface. The velocity of these minute fuel drops meanwhile has been very greatly reduced. At this period, the very hot and dense, powerfully twirling air, which in applicant's engine, preferably is compressed to one twentieth, more or less, of its atmospheric volume, at temperatures of 1200 degrees F., more or less, continues to rapidly break up, evaporate and gasify the fuel. Mixture of gas and air, under these conditions, ignites and burns almost instantaneously. As soon as a portion of the fuel is ignited, heat radiation, which increases with the fourth power of the temperature, becomes the dominant factor, accelerating gasifying and combustion of injected fuel to such a degree, that fuel thereafter is burned up substantially as quickly as it is injected. Ever since beginning of Diesel engine development, mechanics have wrongly identified quick combustion with explosion. Whereas explosion is quick combustion, the reverse is not necessarily true. On the contrary, applicant heretofore explained, that explosion within a Diesel engine, can only be avoided by almost instantaneous combustion at the beginning of fuel injection. This has been accomplished by the writer to a high degree in his above mentioned U. S. patents and it is accomplished to a still higher degree in his present invention, because he produces herein more continuous powerful air- and gas-twirl than heretofore, which is essential in a very highly supercharged power unit, of the type set forth and explained by applicant. Applicant heretofore stated, that the gases overflow from his power unit at very high pressures and temperatures and should be utilized and further expanded within a low pressure power unit, similarly as shown by him heretofore, or the gases may be utilized in a gas turbine, as successfully accomplished in many power plants heretofore. Theoretically, compound power plants operate most efficiently with extremely high supercharging, resulting in overflow of combustion products at relatively very high pressures and temperatures. Combustion products overflowing from such high pressure power units, furthermore can be employed very efficiently in connection with jet-propelled airplanes. Similar combinations have been reported used recently very successfully in high speed airplanes and in locomotives. Applicant's purpose, as stated, is to produce a high pressure power unit, of very high M. I. P., wherein the gas- and air-overflow can be utilized for generating additional power or propulsion, as the case may be.

Applicant's present invention, furthermore consists in the peculiar construction of his piston and cylinder and in his novel arrangement of cooling-fluid ports and cooling-fluid passages of constant cubic contents. The power piston and power cylinder and the crosshead and crosshead guide, are of same diameters and bores, respectively, producing cooling-fluid passages of constant cubic contents during the reciprocating piston motion, permitting steady, rapid movement of cooling-fluid through the passage or passages, at moderate, approximately at least constant cooling-fluid pressure. The construction of the piston and the arrangement of the ports and cooling-fluid passages, have been clearly illustrated in Figs. 1 to 4. As stated, the first cooling-fluid passage 18 is separated from the third cooling-fluid passage 18' by longitudinal webbs 25'. The third cooling-fluid passage 18' is in direct communication with the second cooling-fluid passage 16' by way

of the perforation or fifth cooling-fluid port 20'. The cross-sectional area of the fifth cooling-fluid port 20', as shown, is only about one third as great as the cross-sectional area of the cooling-fluid port 21, causing only about 25 per cent of the total amount of the cooling-fluid to flow from the second cooling-fluid passage 16', through the fifth cooling-fluid port 20' directly into the outer end portion of the third cooling-fluid passage 18' and causing about 75 per cent of the total amount of the cooling-fluid to flow axially outwardly through the second cooling-fluid passage 16', internally cooling the power piston wall containing the piston rings, whereupon the cooling-fluid flows axially inwardly through the radially interior space 16'' and through the third cooling-fluid port 21, into the third cooling-fluid passage 18', from where all cooling-fluid escapes through the fourth cooling-fluid port 19'. The purpose of this construction, is, to prevent accumulation of hot air, or hot lubricant, or of gases, within either one of the cooling-fluid passages 18 or 18', which purpose is obtained, because the perforations or cooling-fluid ports 20 and 20' communicate with the axially outer or upper end of the cooling-fluid passages 18 and 18' and because of very strong, non-interrupted, steady cooling-fluid movement through the passages. As shown, the perforation or cooling-fluid port 21 communicates with the third cooling-fluid passage 18' further axially inwardly than the fifth cooling-fluid port 20'. As stated by the writer, it is important to produce non-interrupted, very steady cooling-fluid movement throughout the ports and passages. This becomes essential in case cooling-lubricant is employed. Cooling lubricant should not be mixed with air or gases which otherwise would cause irregular flow, reducing internal cylinder cooling. Accumulation of hot air or gases are prevented within the hollow power piston adjacent to the piston top, because of steady, high cooling-lubricant velocity only in one direction.

Referring now to Figs. 5, 6 and 7, another novel piston construction is shown, wherein the power piston and power cylinder and the crosshead and crosshead guide, respectively, are of same diameters and bores and wherein a single annular-shaped cooling-fluid passage 18'', of constant cubic content, is provided between the axially middle piston portions 14 and the engine cylinder. In this construction, the axially middle piston portions preferably are of smaller diameter than the power piston and crosshead. The construction furthermore differs from the construction shown hereinbefore because the radially interior space 16'', as shown, continues axially inwardly throughout the axially middle piston portions, communicating with the hollow crosshead and with the crankcase, (not shown herein). As illustrated, the diameter of the radially interior space or port 16'' is reduced near its axially inner end. The purpose of this construction, is, to increase the velocity of the cooling-fluid at the cooling-fluid outlet. It should be explained, that unless the cooling-fluid velocity at the outlet, always is at least as great as the maximum piston speed, during the reciprocating piston motion, more or less air is momentarily sucked into the radially interior space, which should be avoided for reasons explained hereinbefore. Either the piston construction shown in Figs. 1 to 4, or the piston construction shown in Figs. 5 to 7, may be employed, provided a sufficiently large amount of cooling-fluid is pumped through the ports and passages and through the radially interior space

16'' at sufficiently high cooling-fluid velocity, maintaining the internal cylinder wall-and piston wall-surfaces sufficiently cool, facilitating lubrication and smooth sliding of the piston and piston rings within the engine cylinder. As illustrated, the piston constructions are similar, except that the piston shown in Figs. 5 to 7 does not contain the webbs 25' and does not contain the peculiar cooling-fluid port 21 and the cylinder does not contain the port 19'. It should be noted however, that if cooling-lubricant is employed in the construction shown in Figs. 1 to 4, no air is sucked into any of the ports or passages, no matter what the engine speed or the velocity of the cooling-lubricant may be, permitting steady, rapid lubricant movement through the ports and passages during the reciprocating piston motion, at all engine speeds, at low lubricant pressure. For the above reasons, the construction shown in Figs. 1 to 4 is somewhat preferable to the construction shown in Figs. 5 to 7, the latter construction requiring somewhat higher cooling-lubricant pressure and more rapid cooling-lubricant circulation. The cooling-lubricant should flow through the hollow crosshead into the crankcase, at sufficiently low temperatures, after internally cooling the power cylinder and power piston, preventing preheated lubricant from heating the bearings. If the amount of circulating cooling-lubricant is very great, the cooling-lubricant, in the construction shown in Figs. 5 to 7, may, on the contrary be employed for cooling the wrist pin bearing. It is evident, that under various circumstances, or conditions, either the construction shown in Figs. 1 to 4, or the construction shown in Figs. 5 to 7, may be preferable.

Applicant's novel constructions, permitting the use of cooling-lubricant, improve lubrication and cooling of the crosshead and crosshead guide, as well as of the power piston and the power cylinder, which is important, because the mean side-thrust taken up by the crosshead and guide is extremely high in connection with very high supercharging and compounding, as shown heretofore in diagrams in applicant's U. S. Patent No. 2,309,968. Additional pressure-feed lubrication, such as usually provided in Diesel engines, must be provided herein. It is necessary, to cool the heated lubricant, before pumping it again through the ports and cooling-fluid passages. It furthermore is advisable, to purify the cooling-lubricant from time to time. The writer did not show means for cooling and purifying the cooling-lubricant, because this has nothing to do with the invention. Any known, convenient means, or method, for cooling and purifying lubricant, may be employed.

Referring now specifically to Fig. 8, a scavenging-and-cooling-and-supercharging-air inlet port 27, is shown, terminating tangentially into axially outermost portions of the power cylinder, producing powerful twirl, or methodical turbulence, during scavenging and supercharging, the twirl continuing during high compression, fuel injection, gasification and combustion, as set forth and explained and claimed by applicant in his above said U. S. patents and in his co-pending application. As heretofore, a reciprocating cylindrical valve 29 may be employed, controlling scavenging- and cooling-air and supercharging-air inlet into the cylinder, the valve having a port 28', connecting the ports 28, whenever the air must overflow, the valve preferably being operated as set forth and explained by applicant in his U. S. Patent No.

2,309,968. The spaces 30 are employed for cooling-water circulation for the purpose of externally cooling the walls containing the reciprocating valve. The valve 29 furthermore preferably is internally cooled, not shown herein, but shown and claimed in applicant's above said previous pending patent application.

It is sufficient to state, that the axially outermost power cylinder portions and the cylinder head, are primarily scavenged and powerfully internally air-cooled, the combustion products, and successively the scavenging- and cooling-air, flowing spirally inwardly through the power cylinder, escaping through the combustion products outlet port 27', while the latter port is uncovered by the power piston, as explained by applicant heretofore, permitting the gases, which at normal engine load, are still under very high pressures and at very high temperatures, to flow from the high pressure power unit into a low pressure power unit, (not shown herein), wherein the gases are further expanded and utilized. The low pressure power unit may consist of a large low pressure power cylinder and piston, such as shown by the writer heretofore, or if conditions or future development in high pressure gas-turbines, or the like, make it advisable, a turbine power unit or jet-propelling may be employed in airplanes for utilizing the kinetic energy of the combustion products overflowing from the high pressure power unit. Fig. 9 shows a cooling-water space 31, which may be necessary, if the power unit is very highly supercharged.

Referring to Fig. 9, the combustion products outlet port 27', as shown, emerges from within the power cylinder axially inwardly of the scavenging- and cooling-air inlet port, in the direction of the gas- and air-twirl produced therein by the tangential air inlet, that is in the opposite tangential direction as the air inlet port. This arrangement is novel and important in connection with applicant's high speed power units, wherein an extremely large amount of scavenging and cooling-air, at normal engine speed and torque, must flow spirally axially inwardly through the power cylinder, escaping through the piston-controlled tangential gas- and air-outlet port of limited cross-section, during time periods of only a few thousandths of a second. It is evident, that in applicant's power unit, scavenging and internal air-cooling and supercharging must be well controlled in order to produce sufficient internal air-cooling, as well as sufficient supercharging. Strong irregular turbulence must be prevented in the cylinder, because this would require additional excess air-overflow pressure to accomplish scavenging under such conditions and because scavenging would be delayed and decreased, whereas supercharging would be greatly increased, causing excessive compression. All of this can be avoided, if substantially perfect uniflow of scavenging-air is produced through the tangential air-inlet port and the cylinder and the piston-controlled tangential gas- and air-outlet port. This construction has been shown and explained in the writer's previous application Ser. No. 501,436. It is claimed herein more broadly, than in the writer's above said previous application.

From the illustrations, it is evident, that the length of the power piston, the length of the piston stroke, the scavenging- and cooling-air inlet port and the combustion products outlet port, are constructed and arranged in such manner, that the power piston, as stated, does not

uncover the combustion products outlet port, while the piston is at or near axially outer dead center position. This is essential, if cooling-lubricant is moved through the cooling-fluid ports and passages. Applicant's power piston, as stated, contains piston packing rings 15' arranged near the axially inner power piston end, (see Figs. 1, 3 and 5), remaining always axially inwardly of the scavenging-air inlet port and of the combustion products outlet port, these latter piston rings providing a tight packing and preventing leakage of cooling-lubricant from the cooling-fluid passage or passages, into and through the scavenging- and cooling-air inlet port and into and through the combustion products outlet port, which is essential, as stated, if cooling-lubricant is moved through the cooling-fluid passage or passages, instead of cooling-air. If, on the contrary, cooling-air is employed, instead of cooling lubricant, the piston-controlled combustion products outlet port and the power piston and the piston stroke, may be arranged such manner, that a portion of the cooling-air escapes from the cooling-fluid passage through the combustion products outlet port, similarly as set forth and explained by applicant in his U. S. Patent No. 2,310,643, while the remaining cooling-air escapes through the hollow power piston.

30 Applicant heretofore explained, that axially outer power cylinder portions, alternately, are internally exposed to very hot combustion products and to extremely large amounts of relatively very cool scavenging-air. The writer furthermore explained, that scavenging- and cooling-air flow rapidly spirally inwardly, through the axially outer and axially middle power cylinder portions, before escaping through the combustion products outlet port. The time periods 35 of successive internal cylinder wall surface exposure to intense heat and to cool air, are extremely small, but the exposed surfaces, nevertheless, become heated and cooled, almost instantaneously, at least skin-deep, during these short time periods, in conformance with known research work and established laws of heat-ray action and heat-convection, as more fully explained by applicant in his U. S. Patent No. 50 2,310,643. In addition to instantaneous powerful internal surface air-cooling of the axially outer and axially middle power cylinder wall portions, by an extremely large volume of cool scavenging-air, in the manner as originally proposed by 45 the writer, applicant furthermore originally recommended strong internal fluid-cooling of axially middle and axially inner power cylinder wall portions, and of the crosshead guide. Applicant originally reasoned, that almost as important, to internally cool these latter cylinder wall portions, by direct contact with very large amounts of cooling-fluid, as it is, to powerfully internally air-cool axially outer and axially middle power cylinder wall portions. As stated 50 in the writer's above said U. S. patents, the power piston and piston rings furthermore are almost instantaneously cooled skin-deep as a result of heat-convection produced between the piston and piston rings and the above said fluid-cooled axially inner power cylinder wall portions, which latter wall portions herein preferably are strongly internally cooled by cooling fluid during short intermediate time periods, before and after the piston reaches inner dead 55 center position. In the writer's present construc-

tions, portions of the power cylinder and the piston rings, are cooled more efficiently, by heat-convection than heretofore, because cooling-fluid is moved uninterruptedly and steadily through the cooling-fluid passage or passages. Moreover, such cylinder wall portions, in applicant's present construction, can be cooled internally far more strongly than heretofore, because cooling-lubricant can be employed herein instead of cooling-air. This was impossible heretofore in known constructions. It should be understood, that heat convection, under otherwise similar conditions, is proportional to the density of the cooling medium and that cooling-lubricant density is very much greater than cooling-air density.

Applicant stated heretofore, that the reciprocating piston and piston rings, to a considerable degree, act as almost instantaneous temperature equalizers of portions of the cylinder wall surface, and vice versa, producing momentarily at least, surface temperatures, facilitating lubrication and reducing sliding friction to a minimum, while the power piston is entirely free of side-thrust.

As stated, the power piston wall portions containing the piston rings, are powerfully internally cooled, preferably by contact with large amounts of cooling-lubricant, flowing closely alongside the internal power piston wall surface, the internal cooling of these power piston wall portions, in turn, producing strong internal cooling of the piston rings and of lubricant within the piston ring grooves, maintaining this lubricant below critical temperatures, at which the lubricant otherwise would carbonize, all of which is essential for continuous lubrication and for safe operation of the engine.

The power piston rings and grooves, as illustrated, are arranged further axially inwardly within the power piston and power cylinder, than customary, and therefore do not get into contact with cylinder wall portions exposed to the most intense heat-ray action during relatively longest time periods. The axially outermost cylinder wall portions, as stated, are protected against internal burning, by powerful cooling-air twirl, produced primarily within these latter cylinder wall portions. The piston rings furthermore are protected against excessive heat-conduction from the piston top, by reduced thickness of the annular piston wall portions arranged between the piston top and the piston rings, as shown, which has been explained and claimed by applicant heretofore.

Referring again to internal fluid-cooling of cylinder wall portions and to internal power piston cooling, which are subjects of applicant's inventions, the writer's present novel construction, as stated, facilitates greater heat-convection and internal cooling than heretofore, because it produces more steady and therefore increased mean cooling-fluid movement, through the cooling-fluid passage or passages, under otherwise similar conditions. It furthermore permits of employment of cooling-lubricant instead of cooling-air, without danger of irregular, sudden, high cooling-lubricant pressures, which otherwise would cause heavy shocks and would have a tendency of producing cooling-lubricant leakage from the cooling-fluid passage or passages into and through the combustion products outlet port, which is entirely avoided herein. In applicant's previous constructions, it was the clearly expressed and illustrated purpose to cause a portion of the cooling-fluid to flow from the cooling-

fluid passage into and through the combustion products outlet port, whereas, on the contrary, it is the purpose of the present construction, to prevent cooling-lubricant from flowing or leaking from the cooling-fluid passage or passages into or through the combustion products outlet port, which latter object is fully accomplished.

In conclusion, heat-convection and internal cooling, as stated, are proportional to the velocity and the weight or density of cooling-fluid, moved through the passage or passages. Whereas cooling-air can be forced to flow through the cooling-fluid passage or passages, at much greater velocity than cooling-lubricant, the total weight or density and the total heat-absorbing capacity of cooling-lubricant, which can be forced to flow through the passage or passages, in applicant's present novel construction, nevertheless, is very much greater than the total weight and heat-absorbing capacity of cooling-air, which can be forced to flow through the passage or passages of limited cross-sectional areas. Cooling-lubricant, furthermore, offers means for internal lubrication, as well as for uniform powerful internal cooling.

The writer's present construction is more plain and more compact than his previous constructions. It can be manufactured more cheaply and can be assembled more easily, than applicant's previous construction. It requires no cooling-fluid valves. It can be constructed of light weight per I. H. P. and as a short-stroke power unit, well adapted for tractors, motor trucks, busses, locomotives and airplanes, whereas applicant's previous, long stroke power unit, is better adapted for heavy, stationary and marine service.

In his above said U. S. patents and pending patent application, the writer has clearly set forth and explained the reasons, why a properly designed, compound, or multi-expansion, compression-ignition, internal combustion engine, will operate with a fraction of the fuel and of the maximum bearing pressures and internal strains, per I. H. P., as a non-supercharged, non-compound, internal combustion engine. A fool-proof, highly supercharged, high pressure power unit, is the necessary pre-requisite for a compound Diesel engine. The problem of constructing such a high pressure power unit is of fundamental importance in the development of Diesel engines. Applicant believes he has solved this problem in a practical manner.

"M. I. P." signifies mean indicated gas pressure during the downward power piston stroke. The abbreviation "sq. i." signifies square inch.

The expression "cooling-fluid passage or passages," signifies a passage or passages, extending alongside portions of the internal cylinder wall surface and alongside of the internal power piston wall surface, means being provided, producing steady, rapid cooling-fluid movement through the passage or passages, for the purpose of practically instantaneous internal surface cooling of cylinder wall-and power piston wall-portions, facilitating efficient lubrication and safe operation of the high pressure power unit.

"Cooling-fluid ports" signifies inlet-and outlet ports into and from a passage or passages.

"Cooling-fluid" includes cooling-air and cooling-lubricant, or the like.

I claim my invention broadly in connection with supercharged, compression-ignition, internal combustion engines, of two cycle or four cycle type.

Various changes in construction may readily

suggest themselves to a mechanic versed in the art and nothing contained herein, is intended to imply, in any manner, that applicant is limiting himself to the constructions shown and to the combinations described herein, except as required by the claims appended hereto.

I claim:

1. A supercharged, compression-ignition, internal combustion power unit, having a cylinder, a cylinder head and a piston, the power unit having an automatically controlled air-inlet port for scavenging and internal air-cooling and supercharging, the power unit having a fuel-inlet port terminating into the compression chamber, the power unit having a piston-controlled outlet port for scavenging air and combustion products, axially outer piston portions serving as power piston sliding snugly within axially outer cylinder portions serving as power cylinder, axially inner piston portions serving as cylindrical crosshead sliding snugly within axially inner cylinder portions serving as crosshead guide, a powershaft, means driving said shaft from said crosshead, said power piston and said crosshead and said power cylinder and said crosshead guide being of one and the same diameter and bore respectively, axially middle piston portions having a cavity and forming together with said cylinder a reciprocating cooling-fluid passage of constant cubic contents during the reciprocating piston motion, said passage extending for the greater portion of the circumference within said cylinder, the power unit having a cooling-fluid port terminating into said cooling-fluid passage and having a second cooling-fluid port emerging from within said cooling-fluid passage, said cooling-fluid ports and said cooling-fluid passage together forming a group, said cooling-fluid passage being arranged in series between and in permanently open communication with said cooling-fluid ports, means being provided, non-disturbed by the reciprocating piston motion, producing uninterrupted, steady, rapid cooling-fluid movement throughout said group solely in one direction.
2. A supercharged, compression-ignition, internal combustion power unit, having a cylinder, a cylinder head and a piston, the power unit having an automatically controlled air-inlet port for scavenging and internal air-cooling and supercharging, the power unit having a fuel-inlet port terminating into the compression chamber, the power unit having a piston-controlled outlet port for scavenging-air and combustion products, axially outer piston portions serving as power piston sliding snugly within axially outer cylinder portions serving as power cylinder, axially inner piston portions serving as cylindrical crosshead sliding snugly within axially inner cylinder portions serving as crosshead guide, a powershaft, means driving said shaft from said crosshead, said power piston and said crosshead and said power cylinder and said crosshead guide being of one and the same diameter and bore respectively, axially middle piston portions having a cavity and forming together with said cylinder a reciprocating cooling-fluid passage of constant cubic contents during the reciprocating piston motion, the power unit having a cooling-fluid port communicating with said passage and having a second cooling-fluid port communicating with said passage, said piston being hollow except the piston top and said crosshead, said hollow piston portions having a perforation serving as the said second cooling-fluid port, said hollow within said piston serving as a second reciprocating cooling-fluid passage of constant cubic contents, said hollow piston portions having a second perforation serving as a third cooling-fluid port providing communication between said hollow within said piston and a second cooling-fluid cavity provided between said axially middle piston portions and said cylinder, said second cavity serving as a third reciprocating cooling-fluid passage of constant cubic contents, the power unit having a fourth cooling-fluid port communicating with said third cooling-fluid passage, the said first said cooling-fluid port, said first said cooling-fluid passage, said second cooling-fluid port, said second cooling-fluid passage, said third cooling-fluid port, said third cooling-fluid passage and said fourth cooling-fluid port, together, forming a group and being arranged in series and in permanently open communication with each other, means being provided, non-disturbed by the reciprocating piston motion, producing uninterrupted, steady, rapid cooling-fluid movement throughout said group solely in one direction.
3. A structure as in claim 2, wherein means are provided, preventing cooling-fluid leakage from the said cooling-fluid passages into and through the said scavenging- and cooling-air inlet port and into and through the said combustion products outlet port during the reciprocating piston motion.
4. A structure as in claim 2, wherein the space within the said hollow power piston is subdivided by a tubular conduit into a substantially annular shaped radially exterior passage serving as the said second reciprocating cooling-fluid passage of constant cubic contents communicating with said second cooling-fluid port and into a radially interior space communicating at its axially outer end, adjacent to said piston top, with said second cooling-fluid passage and communicating at its axially inner end with said hollow within said axially middle piston portions and the said third cooling-fluid passage, the said third cooling-fluid passage being separated from said first said cooling-fluid passage by axial webbs arranged on said axially middle piston portions, said third cooling-fluid passage communicating with the said fourth cooling-fluid port, the said first said cooling-fluid port, said first said cooling-fluid passage, said second cooling-fluid port, said second cooling-fluid passage, said radially interior space, said hollow within said axially middle piston portions, said third cooling-fluid port, said third cooling-fluid passage and said fourth cooling-fluid port, together, forming a group and being arranged in series and in permanently open communication with each other during the reciprocating piston motion, means being provided, non-disturbed by the reciprocating piston motion, producing uninterrupted, steady, rapid cooling-fluid movement throughout said group solely in one direction.
5. A structure as in claim 2, wherein the space within the said hollow power piston is subdivided by a tubular conduit into a substantially annular shaped radially exterior passage serving as the said second cooling-fluid passage communicating with the said second cooling-fluid port and into a radially interior space communicating at its axially outer end, adjacent to said piston top, with said second cooling-fluid passage and communicating at its axially inner end with said hollow within the said axially middle piston por-

tions, the said third cooling-fluid port passing through the wall of said axially middle piston portions adjacent to said crosshead and permitting communication between said hollow within said axially middle piston portions and the said third cooling-fluid passage, said third cooling-fluid passage being separated from said first said cooling-fluid passage by axial webbs arranged on said axially middle piston portions, said third cooling-fluid passage communicating with the said fourth cooling-fluid port, the power unit having a fifth cooling-fluid port passing through the wall of said hollow axially middle piston portions adjacent to said power piston and permitting direct communication between said second cooling-fluid passage and the axially outer end portion of said third cooling-fluid passage, the said first said cooling-fluid port, said first said cooling-fluid passage, said second cooling-fluid port, said second cooling-fluid passage, said radially interior space, said hollow within said axially middle piston portions, said third cooling-fluid port, said third cooling-fluid passage and said fourth cooling-fluid port, together, forming a group and being arranged in series and in permanently open communication with each other, means being provided, non-disturbed by the reciprocating piston motion, producing uninterrupted, steady, rapid movement of a portion of said cooling-fluid throughout said entire group solely in one direction, the arrangement being such, that a portion of said cooling-fluid flows from said second cooling-fluid passage through said fifth cooling-fluid port directly into the axially outer end portion of said third cooling-fluid passage.

6. A structure as in claim 1, wherein the said power piston, the said axially middle piston portions and the said crosshead are hollow, except the piston top, said hollow axially middle piston portions being perforated adjacent to said power piston, said perforation serving as the said second cooling-fluid port, said hollow within said piston and within said crosshead serving as a second reciprocating cooling-fluid passage of constant cubic contents during the reciprocating piston motion and communicating with said second cooling-fluid port, said first said cooling-fluid port, said first said cooling-fluid passage, said second cooling-fluid port and said second cooling-fluid passage, together, forming a group and being arranged in series and in permanently open communication with each other, means being provided, non-disturbed by the reciprocating piston motion, producing non-interrupted, steady, rapid cooling-fluid movement throughout said group solely in one direction.

7. A structure as in claim 1, wherein the said power piston, the said axially middle piston portions and the said cross head are hollow, except the piston top, said hollow axially middle piston portions being perforated adjacent to said power piston, said perforation serving as the said second cooling-fluid port, the space within said hollow power piston being subdivided by a tubular conduit into a substantially annular-shaped radially exterior passage serving as a second reciprocating cooling-fluid passage of constant cubic contents during the reciprocating piston motion, communicating with said second cooling-fluid port and into a radially interior space communicating at its axially outer end, adjacent to said piston top, with said second cooling-fluid passage and communicating at its axially inner end with said hollow within the axially inner end of said axially middle pis-

ton portions and with said hollow within said crosshead, the said first said cooling-fluid port, the said first said cooling fluid-passage, said second cooling-fluid port, said second cooling-fluid passage, said radially interior space and said hollow within the axially inner end portion of said axially middle piston portions and said hollow within said crosshead, together, forming a group and being arranged in series and in permanently open communication with each other, means being provided, non-disturbed by the reciprocating piston motion, producing non-interrupted, steady, rapid cooling-fluid movement throughout said group solely in one direction.

8. A structure as in claim 1, wherein said cooling-fluid ports and said cooling-fluid passage are adapted for circulating cooling-lubricant through said ports and said passage, the piston stroke, the axial length and shape of said passage, and the location of said cooling-fluid ports, being such, that said passage does not communicate with said scavenging air inlet port and with said combustion products outlet port during the reciprocating piston motion, the arrangement permitting uninterrupted, steady cooling-lubricant movement through said cooling-fluid ports and said cooling-fluid passage during the reciprocating piston motion, means being provided, including a piston packing ring arranged adjacent to the axially inner end of said power piston, in such manner, that cooling-lubricant leakage is prevented from said passage, past said piston packing ring into said scavenging-air inlet port and into said combustion products outlet port.

9. A structure as in claim 1, wherein said scavenging-and supercharging-air inlet port is terminating tangentially into axially outermost cylinder portions, and wherein said air-and combustion products-outlet port emerges from within said cylinder further axially inwardly than said scavenging-air inlet port said air-and combustion products emerging from within said cylinder tangentially in the direction of the twirl produced by said tangential air-inlet port, thus improving uniflow, permitting higher scavenging-air velocity, increasing internal air-cooling of the cylinder wall and piston top and facilitating lubrication of said power cylinder.

10. A structure as in claim 1, wherein said cooling-fluid ports and said cooling-fluid passage contain cooling-lubricant and are arranged axially inwardly from said scavenging-air inlet port and from said combustion products outlet port, the piston stroke and the axial length of said cooling-fluid passage and the arrangement of said ports, being such, that said passage does not communicate with said scavenging-air inlet port and with said combustion products outlet port during the reciprocating piston motion, means being provided producing uninterrupted, steady cooling-lubricant movement through said passage, and means preventing cooling-lubricant leakage from said passage past said piston into said scavenging-air inlet port and into said combustion products outlet port.

11. A structure as in claim 1, wherein the wall of said cylinder has a cooling-fluid inlet port and a cooling-fluid outlet port arranged axially inwardly of said scavenging-air inlet port and of said combustion products outlet port, each of said cooling-fluid ports communi-

cating uninterruptedly with a cooling-fluid passage provided between said piston and the major axially middle portions of said cylinder, said cooling-fluid ports being arranged in permanently open communication with each other by way of said cooling-fluid passage during the reciprocating piston motion, means being provided producing non-interrupted, steady, rapid cooling-fluid movement through said cooling-fluid inlet port, said passage and said cooling-fluid outlet port, effecting strong internal fluid-cooling of said major axially middle cylinder portions during the operation of the power unit.

12. A structure as in claim 1, wherein a cooling-fluid inlet port and a cooling-fluid outlet port are provided within the wall of said cylinder axially inwardly of said scavenging-air inlet port and of said combustion products outlet port, portions of said piston being hollow, said hollow serving as a cooling-fluid chamber within said piston, a cooling-fluid inlet cavity and a cooling-fluid outlet cavity being provided and arranged between said piston and said cylinder wall respectively, said hollow piston portions having two perforations, said perforations permitting communication between the said cavities and said chamber respectively, the said cooling-fluid-inlet port, said cooling-fluid-inlet cavity, one of said perforations, said chamber, the other one of said perforations, said cooling fluid-outlet cavity and said cooling-fluid-outlet port, together, forming a group and being arranged in series and in permanently open communication with each other during the reciprocating piston motion, means being provided, producing non-interrupted, steady cooling-fluid movement throughout said group, for the purpose of strongly internally fluid-cooling said piston during the operation of the power unit.

13. A supercharged, compression ignition, internal combustion, power unit, having a cylinder and a piston, said piston sliding snugly within said cylinder, the power unit compression chamber being arranged substantially concentrically with the cylinder axis and being in substantially non-restricted communication with said cylinder, the power unit having a fuel-inlet port adapted for fuel injection into said compression chamber, an automatically controlled scavenging- and supercharging-air inlet port being provided terminating tangentially into axially outermost cylinder portions primarily scavenging and internally air-cooling said compression chamber and said axially outermost cylinder portions, the power unit having a piston-controlled scavenging-air and combustion products-outlet port emerging from within said cylinder tangentially in the direction of the twirl produced by said tangential air-inlet and being arranged axially inwardly from said scavenging- and supercharging-air inlet port, the arrangement producing powerful, substantially unobstructed air- and gas-twirl around the cylinder axis primarily within said compression chamber and said axially outermost cylinder portions, said twirl continuing uninterruptedly during scavenging, supercharging, fuel-injection, gasification and combustion, said tangential air inlet port and said tangential gas- and air-outlet port co-operating in producing uniflow of air- and combustion products, facilitating scavenging and internal air-cooling and lubrication of said cylinder.

14. A supercharged, compression ignition, internal combustion power unit, having a cylinder of uniform bore, a piston sliding snugly within

said cylinder, axially outer piston portions serving as power piston sliding snugly within axially outer cylinder portions serving as power cylinder, axially inner piston portions serving as crosshead sliding snugly within axially inner cylinder portions serving as crosshead guide, said power piston and said crosshead and said power cylinder and said crosshead guide being of one and the same diameter and bore respectively, axially middle piston portions being of lesser diameter than said power piston and said crosshead, the power unit compression chamber being arranged substantially concentrically with the cylinder axis and being in substantially non-restricted communication with axially outer cylinder portions, the power unit having a fuel inlet port adapted for fuel injection into said compression chamber, the power unit having an automatically controlled scavenging- and supercharging-air inlet port terminating tangentially into axially outermost cylinder portions primarily scavenging and powerfully internally air-cooling said compression chamber and said axially outermost cylinder portions, said power cylinder having a power piston controlled scavenging-air and combustion products outlet port emerging from within said cylinder tangentially in the direction of the twirl produced by said tangential air-inlet port, said piston-controlled port being arranged axially inwardly from said scavenging- and supercharging-air inlet port, the arrangement being such that powerful substantially unobstructed air- and gas-twirl are produced within said power cylinder around said cylinder axis, said twirl continuing uninterruptedly during scavenging, supercharging, fuel-injection, gasification and combustion, said tangential piston controlled gas- and air-outlet port, facilitating gas- and air-overflow, improving uniflow and scavenging and internal air-cooling of the power cylinder and of the top of said piston as a result of increased heat convection from the hot wall surfaces to the twirling cooling-air, thus facilitating lubrication, the power unit having a power shaft, means driving said shaft from said piston.

15. A construction as in claim 1, wherein the wall of said cylinder has a cooling-fluid inlet port and a cooling-fluid outlet port arranged axially inwardly of said scavenging-air inlet port and said combustion products-outlet port, a cooling-fluid cavity being provided between axially middle piston and cylinder portions, said cooling-fluid ports and said cavity being arranged in permanently open communication with each other by way of said cavity during the reciprocating piston motion, means being provided producing non-interrupted, steady cooling-fluid movement through said cooling-fluid inlet port and said cavity and said cooling-fluid outlet port, for the purpose of effecting strong internal fluid-cooling of axially middle cylinder portions during the reciprocating piston motion.

16. A structure as in claim 1, wherein the wall of said cylinder has a cooling-fluid inlet port and a cooling-fluid outlet port arranged axially inwardly of said scavenging-air inlet port and said combustion products outlet port, axially outer and axially middle portions of said piston being hollow, said hollow serving as a cooling-fluid chamber, a cooling-fluid inlet cavity and a cooling-fluid outlet cavity being provided and arranged within the axially middle portions of said piston and extending alongside the greater portion of the periphery within said cylinder, said hollow piston portions having two perfora-

tions permitting communications between said cavities and said chamber respectively, said fluid-inlet port, said fluid-inlet cavity, one of the said perforations, said chamber, the other one of the said perforations, said fluid-outlet cavity and said fluid-outlet port, together, forming a group and being arranged in series and in permanently open communication with each other during the re-

ciprocating piston motion, means being provided, producing non-interrupted, steady cooling-fluid movement throughout said group, for the purpose of strongly internally fluid-cooling axially middle portions of said cylinder and of said piston during the operation of the power unit.

FRANCIS MARBURG.
